(57) CLAIM

The ornamental design for a lighter with clip, as shown and described.

DESCRIPTION

FIG. 1 is a front view of the lighter with a clip of my new design,

FIG. 2 is a rear view thereof,

FIG. 3 is a right side view thereof which is symmetrical with left side view thereof;

FIG. 4 is a top view thereof; and,

FIG. 5 is a bottom view thereof.

The broken line environmental showing is for illustrative purposes only and forms no part of the claimed design.
